DESIGN FOR A STONE SETTING FOR RINGS

Jacob Karlan, Mount Vernon, N. Y.

Application January 25, 1943, Serial No. 109,342

Term of patent 3½ years

To all whom it may concern:

Be it known that I, Jacob Karlan, a citizen of the United States, residing in Mount Vernon, county of Westchester, State of New York, have invented a new, original, and ornamental Design for a Stone Setting for Rings, of which the following is a specification, reference being had to the accompanying drawing forming part thereof.

Figure 1 is a top view of the stone setting showing my new design.

Figure 2 is an elevation of the stone setting.

Figure 3 is a bottom-up view of the stone setting.

I claim:

The ornamental design for a stone setting for rings, as shown.

JACOB KARLAN.
